UNITED STATES PATENT OFFICE.

MORRELL J. UFFORD, OF KANSAS, ILLINOIS.

FIRECRACKER-GUN.

1,327,747.

Specification of Letters Patent. Patented Jan. 13, 1920.

Application filed June 5, 1919. Serial No. 301,956.

To all whom it may concern:

Be it known that I, MORRELL J. UFFORD, a citizen of the United States, residing at Kansas, in the county of Edgar and State 5 of Illinois, have invented certain new and useful Improvements in Firecracker-Guns, of which the following is a specification, reference being had to the accompanying drawings.

10 This invention relates to toy firearms, and more particularly to toys designed to simulate a rapid fire gun and designed for the firing of fire crackers.

15 The general object of the invention is the provision of a toy of this character which is very simple in construction and easy of operation, and in which the fire crackers are fed one by one from a hopper and carried to a firing chamber where they are exploded.

20 A further object is to provide a firing chamber with swinging side walls so that when the explosion takes place, these side walls will be projected with considerable force against stop fins mounted upon the 25 body of the gun, thus increasing the noise produced by the explosion of the fire crackers.

A further object is to provide very simple 30 means for carrying a single cracker from the feeding hopper of the gun into the firing chamber, and in this connection to provide means for igniting the fire cracker during its passage from the hopper into the firing chamber.

35 Other objects will appear in the course of the following description.

My invention is illustrated in the accompanying drawings, wherein:-

Figure 1 is a side elevation of my fire 40 cracker gun;

Fig. 2 is a vertical sectional view thereof;

Fig. 3 is a fragmentary top plan view, the feeding hopper being in section;

Fig. 4 is a section on the line 4—4 of 45 Fig. 2; and

Fig. 5 is a section on the line 5—5 of Fig. 2.

Referring to these drawings, it will be seen that my toy gun comprises a body 10 having a barrel 11 projecting therefrom, and a tripod 12 upon which the body is preferably rotatably mounted. The lower extremities of the tripod limbs are provided with flanges or feet through which screws 55 may be passed in order to attach the tri-

pod to a wagon, platform, or other desired support.

The interior of the body 10 is formed to provide a firing chamber 14, the bottom of which is formed by an inclined pan 15 and the sides 16 of which are formed of metal, pivoted at their upper edges so as to swing outwardly in the body 10. Coil springs 17 may surround the pintles of these hanging walls 16 so as to yieldingly resist any outward movement of these hanging walls. When a cracker is exploded upon the pan 15, these walls will be blown laterally outward and will crash against fins or other abutments 18 projecting inward from the 70 side walls of the body 10.

For the purpose of conveying a fire cracker from the feeding hopper to the firing pan, and at the same time cutting off all communication between the feeding hopper 75 to the firing pan at the time the cracker is being fired, and further provide means for lighting the fire cracker as it passes from the feeding hopper into the firing pan, I provide within the firing chamber a roller 80 19, the shaft 20 of which projects out through the body and is provided with a crank 21, this roller at one or more points on its periphery being formed with a groove 22 adapted to receive the cracker through an 85 opening 23 formed in the casing wall, and carry this cracker downward to the firing pan, the cracker being held in place, in the movement of the roller from the time it is received to the time it is discharged onto 90 the firing pan, by an apron 24 which extends around the circumference of the roller 19 a suitable distance to this end.

For the purpose of discharging crackers one by one through the opening 23, I may 95 provide a hopper, as it may be termed, comprising two parallel sets of guides 25, these guides, if the hopper is in circular form, being disposed concentric to each other and one set of guides being spaced from the 100 other set of guides a distance slightly greater than the diameter of a fire cracker, and the hopper, of course, having a length approximately that of a fire cracker. This hopper may have imperforate walls or be of skeleton formation as desired. Under any circumstances, however, one side of the hopper or guide will be open and for the purpose of feeding the fire crackers along this hopper or guide, I provide a follower 26 which I 110

have illustrated as being mounted upon an arm 27, this arm in turn being pivoted at 28 to any suitable support, as for instance, a bracket extending from the side wall of the 5 body or casing and there being a coiled spring 29 which engages this arm and tends to move it and the follower from the entrance end of the guide or hopper toward the opening 23. The spring is relatively 10 light and just sufficient to cause the positive feeding of a cracker into the groove in the roller when the groove has registered with the opening 23.

For the purpose of igniting the fuse of 15 the cracker, I provide a housing 30 upon the side of the body, in which is carried a candle or burner having a flame, and the flame of this candle or other burner is disposed in such position that as the roller 19 moves 20 from its receiving position to its discharging position, the fuse of the cracker will be carried through the flame, thus igniting the fuse. The roller is operated, of course, at such a speed as to make certain an ignition 25 of the fuse.

The operation of the invention will be obvious from what has gone before. The crackers A are disposed in the hopper or guide and the candle or other burner lighted. 30 Then the roller is rotated by means of the crank 21 and one by one the crackers are carried by the roller from the receiving opening 23, past the candle, the fuse a ignited, and then the cracker is discharged 35 onto the firing pan and then explodes, blowing the wings or side walls 16 outward and causing them to clash against the side wall of the body, thus adding to the noise produced by the exploding cracker. The legs 40 of the tripod, as before remarked, are provided with feet whereby the tripod may be attached to a toy wagon or to any other platform and fastened firmly in place. It is obvious that the device may be made in 45 various sizes to accommodate various sizes of crackers, and it will also be obvious that the device may be made very cheaply of sheet metal or may be made of cast metal, or of wood and metal, and that it may be formed 50 so as to simulate very closely a rapid fire gun. It is to be particularly noted that the roller 19 performs three functions, that it acts as a means for conveying the crackers one by one from the hopper to the firing 55 chamber, that it forms means for separating the firing chamber from the hopper so as to prevent the ignition of any crackers within the hopper by the discharge of the cracker in the firing chamber, and further it provides means for carrying the fuse of the 60 cracker past an igniting member.

It will be noted from Fig. 5 that the support 30 is a housing which is supported upon the side of the body 10 preferably at 65 the junction of the guideway or hopper 25

with the housing, as at this point the fire cracker comes to rest during a complete rotation of the roller so as to give time for the fuse a of the cracker A to ignite. I do not wish to be limited to this particular 70 location for the igniting means, but if this igniting means were disposed in the path of movement of the fire cracker as it is carried around by the roller 19, it would move so swiftly through the flame of the candle, 75 lamp or other device supported in the housing that it might not ignite. Of course, it will be understood that the body of this device is preferably releasable from the tripod so that the gun proper may be connected 80 with any suitable support. The burnt crackers are discharged from the inclined pan 15 through an opening in the rear end of the casing 10, if desired.

I do not wish to be limited to the particular 85 form of the hopper, nor to the particular means for urging the crackers along the hopper, as it is obvious that a hopper might be provided in which the crackers were fed by gravity to the operating roller.

I claim:

1. A fire cracker gun of the character described comprising a body having a firing chamber, a hopper conveying the fire crackers to an opening in the body, and igniting 95 means mounted on the body, means for carrying the fire crackers one by one from the discharge end of the hopper into the firing chamber, and passing the fuse of the fire crackers through the igniting means.

2. In a toy fire cracker gun, a body having a barrel, the body being formed with a firing chamber having hinged walls adapted to be blown apart by the explosion of a cracker.

3. In a toy fire cracker gun, a body having a barrel, the body being formed with a firing chamber having hinged walls adapted to be blown apart by the explosion of a cracker, and members projecting inward from the side walls of the body and against 110 which said side walls of the firing chamber will strike when the fire cracker is exploded.

4. A fire cracker gun including a body having a firing chamber, a hopper discharging into the body above the firing chamber, 115 and a rotatable member mounted within the body and having a groove adapted to receive the fire cracker and convey it from the hopper to said chamber, and means disposed in the path of movement of the cracker for igniting the fuse thereof.

5. A fire cracker gun including a body formed with a firing chamber, means for supporting an igniting flame within the body, and means for moving the fire crackers one by one from a receiving point to said firing chamber, and carrying the fuses of said fire crackers through said flame.

6. A toy gun of the character described including a body having a firing chamber,

a hopper discharging into the body at a point remote from the firing chamber, a roller having a groove adapted to receive fire crackers one by one, the rotation of the 5 roller carrying each fire cracker from the hopper to the firing chamber and dropping it thereinto, and an igniting flame disposed in the path of movement of the fire cracker and adapted to ignite the fuse thereof prior 10 to the cracker being received within the firing chamber.

7. A fire cracker gun of the character described including a body having a firing chamber and a receiving opening, a pair of 15 arcuate guides extending from the receiving opening and adapted to receive a series of fire crackers, a follower urging said fire crackers toward the opening in the body, a roller mounted within the body and having a longitudinally extending groove adapted to register with the receiving opening as the roller 20 is rotated to thereby carry the fire crackers from the hopper to the firing chamber, and an igniting element disposed in the path of 25 movement of the fire crackers and adapted to ignite the fuses thereof.

8. A fire cracker gun of the character described including a body having a firing chamber and a receiving opening, a pair of 30 arcuate guides extending from the receiving opening and adapted to receive a series of fire crackers, a follower urging said fire crackers toward the opening in the body,

said follower being disposed between the guides and having a radially extending arm 35 to carry the follower between the guides, and a spring urging said arm to carry the follower toward the receiving opening of the body, a roller mounted within the body and having a longitudinally extending groove 40 adapted to register with the receiving opening as the roller is rotated to thereby carry the fire crackers from the hopper to the firing chamber, and an igniting element disposed in the path of movement of the fire 45 crackers and adapted to ignite the fuses thereof.

9. A fire cracker gun of the character described comprising a body having a firing chamber, means for conveying fire crackers 50 one by one into said chamber, and means for igniting the fire crackers as they are carried on said conveying means to said chamber.

10. In a fire cracker gun, a firing chamber, and means for conveying fire crackers 55 one by one into said firing chamber comprising a rotatable body forming one wall of the firing chamber and having a longitudinally extending groove therein to receive a fire cracker.

In testimony whereof I hereunto affix my signature in the presence of two witnesses.
